DEVICE FOR PLACING BAG COVERS OVER GARMENTS

Daniel J. McCarty, Los Angeles, Calif.

Application June 14, 1937, Serial No. 148,077

1 Claim. (Cl. 226—18)

This invention relates to a device that may be used for the insertion of garments into bag coverings.

This application is a continuation in part of an application, Serial No. 139,442, filed in the name of Daniel J. McCarty on April 28, 1937, for "Device for placing bag covers over garments."

In garment cleaning and pressing establishments, it has now become the custom to place a paper bag or covering over the garment after cleaning or pressing, and prior to delivery to a customer. Such bags are usually arranged with an open bottom, so that they may be slipped over a garment hung on a conventional clothes hanger. The clothes hanger is usually provided with a hook that can project through a small opening in the top of the bag.

The act of placing the bag over a garment hanging on a hanger, has been clumsy and time consuming. Especially is this true where the garment is a full-length one; such as a woman's dress, or an overcoat or a suit of clothes.

It is one of the objects of this invention to provide a device that makes it possible to place such covering bags easily over the garment.

It is another object of the invention to make it possible to store a large number of bags in a convenient manner and in a position ready for placing them over garments as desired.

It is another object of this invention to provide a convenient although inexpensive mechanism, including an enclosing cabinet, to facilitate the storage of a number of bags for use; that is, with the open end at the bottom, and in elevated position.

This invention possesses many other advantages, and has other objects which may be made more easily apparent from a consideration of one embodiment of the invention. For this purpose there is shown a form in the drawings accompanying and forming part of the present specification. This form will now be described in detail, illustrating the general principles of the invention; but it is to be understood that this detailed description is not to be taken in a limiting sense, since the scope of this invention is best defined by the appended claim.

Referring to the drawings:

Figure 1 is a front elevation of a cabinet used in connection with the invention; the carriage being shown in partly elevated position;

Fig. 2 is an enlarged sectional view taken along plane 2—2 of Fig. 1, but with the carriage in fully elevated position, and also illustrating the apparatus located below the cabinet;

Fig. 3 is an enlarged sectional view taken along plane 3—3 of Fig. 1;

Fig. 4 is a fragmentary enlarged detail sectional view illustrating the elevating and lowering mechanism, some of the parts being broken away to reduce the size of the figure;

Fig. 5 is an elevation of a pole structure, partly broken away, which is adapted to cooperate with the cabinet;

Fig. 6 is an enlarged sectional view taken along plane 6—6 of Fig. 5;

Fig. 7 is a fragmentary enlarged elevation taken from the front of Fig. 5;

Fig. 8 is an elevation of one of the garment bags to be utilized in connection with the invention;

Fig. 9 is a fragmentary view similar to Fig. 2, showing the manner in which a garment bag is being placed over a garment on a hanger; and

Fig. 10 illustrates the position of the pole structure preparatory to the removal of the garment and its hanger from the pole structure.

The garment bag 1 (Figs. 2, 8, 9 and 10) is shown as of conventional form. It is open at the bottom and has an upwardly extending tab 2. The upper end of the bag 1 converges, and there is an opening 3 immediately below the tab 2 formed as a narrow slit, through which the hook of a garment hanger may pass.

In the present instance the garment bags 1 are supported, at their upper ends by the aid of the tabs 2 through which passes a supporting member 4 (Figs. 2 and 9). This supporting member is conveniently made in the form of a rod or spike with a pointed end which may be forced through the tabs 2. Furthermore, the support 4 is of sufficient length to accommodate a comparatively large number of bags 1, only a few being shown in Figs. 2 and 9. These bags 1 thus are supported with their large open ends directed downwardly, so that the bags may be readily pulled downwardly over a garment.

In order that any one of the bags 1 may be pulled downwardly over a garment and its hanger, provisions are made for supporting a garment with its hanger immediately below the bags 1. The structure for effecting this result is shown most clearly in Figs. 5, 6, 7, 9 and 10.

In order to utilize this structure now to be described, it is desirable that the bags 1 be supported at a sufficiently high level above the floor 5 so that an operator in standing position may be able conveniently to grasp the bottom of one of the bags 1, so as to pull it downwardly.

Immediately below the garment bags 1 there

is a structure for supporting a garment hanger 7 (Figs. 1, 2, 9 and 10). This supporting structure includes a pole 6 which carries at its upper end a bracket 8 as of wire. This bracket 8 is shown most clearly in Fig. 5. It is provided with a hook-like configuration at one side over which the garment hanger hook may be placed.

Pole 6 is adapted to be maintained normally in the upright position shown in Fig. 9. The garment 9 hung on the hanger 7 is supported at the top of the pole 6 by the aid of the bracket 8. In this position one of the bags 1 can be pulled over the garment 9 by pulling the bag downwardly, tearing its tab 2. In Fig. 9, one of the bags is shown as being partly pulled over the pole and the garment; in Fig. 10 the bag 1 is shown as completely pulled over the pole 6, the hook of the garment hanger 7 projecting through the open slit 3.

20 In order to facilitate removal of the garment 9 with its hanger 7 from the pole 6, this pole is pivotally supported as by the aid of a bracket structure 10. This bracket structure includes a vertical attaching plate 11 (Figs. 2, 5 and 7), 25 adapted to be fastened to the wall below the bags 1. This vertical attaching plate has a pair of spaced upwardly directed bracket arms 12 which support a frame 13. This frame 13 is formed of two spaced arms having horizontal extensions 14 30 and 15 (Fig. 6), as well as a lower connecting piece 16. Located below the horizontal extensions 14 and 15, a pivot pin 17 is supported in the vertical arms of frame 13, and passes through the interposed lower end of the pole 6. In this way 35 the pole is permitted to swing about the pivot pin 17. Accordingly when it is desired to unload the garment 9 and the hanger 7 from the pole 6, the pole structure may be tilted forward as shown in Fig. 10 and away from the lower ends of bags 1. 40 The bag 1, garment hanger 7, and garment 9 may then be removed off of the pole 6 for delivery of the garment to a customer. The bracket structure 10 of course forms a permanent installation beneath the bags 1.

45 Provisions are made to ensure the return of the pole 6 to the vertical position of Fig. 9 as soon as it is released from the unloading position of Fig. 10. For this purpose a tension spring 18 (Figs. 5, 7, 9 and 10) is provided. One end 50 of this tension spring is engaged in an anchoring eye 19 attached to the bottom of the pole 6. The lower end of the spring 18 is fastened to an eye-bolt 20 passing through the strip 16 and engaged for adjustment purposes by a wing nut 21. 55 It is apparent that the spring 18 is stretched when the pole 6 is moved out of its vertical position. When the pole is released, the force of the spring 18 urges the pole back to the position of Fig. 9. By appropriate adjustment of the wing 60 nut 21, the restoring force can be adjusted as desired.

A detachable connection is so arranged that the pole 6 is detachably retained in the vertical position of Fig. 9 until the operator releases it as by pulling pole 6 forward. For this purpose, 65 as shown most clearly in Figs. 5 and 6, the horizontally extending arms 14 and 15 of bracket 10 are joined by a strap 22, to which is fastened a U shaped spring clip 23. Adapted to enter between these spring clips, and to be detachably held thereby, there is a pointed member 24 having sloping faces and attached as by riveting to the pole 6. Thus when the pole 6 is released 70 from the position of Fig. 10, the spring 18 moves 75 the pole 6 toward the upright position, and when

it is in substantially upright position, the force of the spring is sufficient to cause the tapered faces of the member 24 to spread the spring arms of the clip 23 apart and to permit the shoulder of the member 23 to be retained detachably back of the outwardly turned lips 25 of the spring clip 23.

For convenience in operation, and as heretofore stated, the bags 1 should be sustained at a height to facilitate ready manipulation of the bags by the operator standing on the floor 5. In order to facilitate loading the bag support 4, there is provided an elevating and lowering mechanism whereby this support 4 may be lowered; and after loading the support 4 with the bags 1 may be elevated to its desired height.

For this purpose there is provided an enclosing cabinet 26 shown to best advantage in Figs. 1, 2, 3 and 4. This cabinet can include the sides 27 and 28 (Fig. 3) having a front glass panel 29, 20 and supported directly on the vertical wall 53. The glass panel 29 makes it possible conveniently to view the bags 1 from the exterior of the cabinet 26.

The lowering and elevating mechanism includes a pulley and drum device and a carriage 30 operated thereby. This carriage supports at its upper end the bag support 4. This support 4 may have a rearwardly extending portion 31, braced by a bracket 32 fastened to the rear wall 30 of the carriage 30. This carriage 30 is adapted to be guided by the aid of vertical guide cleats 33 and 34 fastened to the inner sides of the side walls 27 and 28. To each of these guides is fastened a longitudinal metal strip 35. The edges 36 of the metal strip 35 project inwardly beyond the guide cleats 33 and 34. These edges are adapted to be engaged within a groove formed between the rear wall of carriage 30 and the rabbeted cleats 36, fastened to the rear of the carriage 30.

The guide members 33, 34 and 35 extend for a material portion vertically within the cabinet structure 26. As shown most clearly in Fig. 2, a pulley 37 is provided near the top of the cabinet over which passes a flexible element such as string or cord 38. One reach of the cord 38 is attached to the extension 31. The other reach of the cord 38 is intended to be wound on a drum 39 located near the bottom of the cabinet. This drum is shown in Fig. 4 as having pintles 40 and 41 journaled in the bearing brackets 42 and 43 fastened to the inside surfaces of the walls 27 and 28. In order to raise and lower the carriage 30, the drum 39 is adapted to be rotated by the aid of a pair of gears 44 and 45. Gear 44 is fastened to the right hand end of drum 39. Gear 45 meshes therewith and is adapted to be rotated by the aid of a handle on the outside of the cabinet. For this purpose the gear 45 has an extending shaft 46 with a square projection 47 that may be received in a ratchet handle or the like. The gear 45 is rotatably supported by the aid of the bracket 43, and also by the aid of a supplemental bracket 48 fastened 65 to the cleat 34.

In order to gain ready access to the drum mechanism, the cabinet may be provided with a door 49 adapted to swing on a vertical axis as by the aid of the hinges 50. The bottom of the 70 cabinet may also be provided with a door 51 that is supported by the aid of the horizontal hinges 52.

The mode of operation of the apparatus is clear from the foregoing. When it is desired 75

to load the support 4 with the garment bags 1, the drum 39 is operated to lower the carriage 30. In its lowered position the carriage 30 extends to near the bottom of the cabinet 26, in which position the bags are placed by the aid of tabs 2 upon the support 4. Then the drum 39 may be operated to bring the carriage 30 to the position shown in Fig. 2. A sufficient number of bags may be thus supported at a convenient level and to provide a supply for a considerable period.

In order to place a bag 1 over a garment, such as 9, the garment hanger 7 is first placed upon the bracket 8 on top of the pole 6. Then one of the bags 1 is pulled downwardly off of the support 4, tab 2 of the bag being torn and the bag finally telescoping over the pole 6 and the garment 9. The pole 6 can now be lowered to the position of Fig. 10, where it is in a convenient position for removing the garment hanger 7 and the garment 9, together with its bag 1. Upon

releasing the pole 6, it will return to the vertical position of Fig. 9.

What is claimed is:

In a device of the character described, a carriage, means supported by the carriage for suspending garment bags layer on layer at their tops, with their open ends directed downwardly, a pivoted rod adapted to support a garment hanger and having an extremity that may be positioned below the bags, and means for moving the carriage in a vertical direction whereby the bags may be positioned optionally at a height to permit ready manipulation thereof, the parts being so proportioned that when the carriage is in its upper position the bags hang with their lower ends adjacent the upper end of said rod, the latter being approximately vertical, and capable of being adjusted to operative position beneath the open ends of the bags.
